UNITED STATES PATENT OFFICE.

FRANK LOWELL BUTLER, OF CHICAGO, ILLINOIS.

SWITCH-SUPPORTING ATTACHMENT FOR ELECTRIC FIXTURES.

1,423,645.

Specification of Letters Patent. Patented July 25, 1922.

Application filed April 25, 1921. Serial No. 464,090.

To all whom it may concern:

Be it known that I, FRANK L. BUTLER, a citizen of the United States, and a resident of Chicago, in the county of Cook and State 5 of Illinois, have invented a new and useful Improvement in Switch-Supporting Attachments for Electric Fixtures, of which the following is a full, clear, and exact description.

10 My invention relates to electric fixtures adapted to be attached to a ceiling and more particularly to electric fixtures having a depending stem.

An object of my invention is to provide 15 in an electric fixture of the type described a stem provided with means adapted for connection with a lighting fixture element and with a switch for controlling the operation of incandescent lamps carried by the 20 lighting fixture element, whereby the lighting fixture elements and the switch are supported by the stem.

A further object of my invention is to provide in an electric fixture of the type described 25 a novel attachment embodied in the stem of the fixture.

A further object of my invention is to provide in an electric fixture of the type described 30 a stem provided with means for supporting a switch close to the stem.

A further object of my invention is to provide a device of the character described in which the number of essential parts is reduced to a minimum and consequently ease 35 of assembly is obtained.

A further object of my invention is to provide a device of the type described that is thoroughly practical commercially.

Other objects and advantages will appear 40 in the following specification, and the novel features of the invention will be particularly pointed out in the appended claims.

45 My invention is illustrated in the accompanying drawings, forming part of this application, in which—

Fig. 1 is a side elevation partly in section showing the use and application of the device.

50 Fig. 2 is a section along the line 2—2 of Figure 1 with parts broken away,

Fig. 3 is a view similar to Fig. 1, showing the use and application of the modified form of the device,

55 Fig. 4 is a view similar to Fig. 1 showing the use and application of still another modified form of the device.

In carrying out my invention in its preferred form, as illustrated in Fig. 1, I provide a stem, indicated generally at 1, for an electric fixture that is operatively connected 60 with a ceiling 2 to depend therefrom. The stem 1 has the usual canopy 3 mounted thereon and maintained in adjusted position relative to the stem by means of a set screw 4 contacting with a tubular member 5 embodied in the stem. A rod 6 is disposed within the tubular member 5 and is connected at its upper end with a fixed support (not shown) so that the lower end thereof which is threaded at 7 extends below the corre- 70 sponding end of the tubular member 5 for connection with means for maintaining the tubular member 5 in adjusted position. In the usual electric fixture construction, a member known as a "loop" is placed on the 75 lower end of the rod 6 or its equivalent to support the tubular member 5 and for connection with electric lighting fixture elements that ordinarily depend from the stem and are supported by the latter. Instead of 80 the usual "loop," I provide an attachment indicated generally at 8 and comprising a body portion 9 having the form of a substantially cylindrical member adapted to enter the lower end of the tubular member 5 85 and being fashioned with a flange 10, thereby providing a seat for the tubular member 5. The body portion 9 has a central threaded opening 11 adapted for engagement with the threaded lower end of the rod 6. Dia- 90 metrically opposed vertically extending grooves 12—12 are provided in the outer wall of the body portion 9, as best seen in Fig. 2. An integral loop extension 13 to the body portion 9 has depending therefrom a 95 chain 14 adapted for connection with an electric lighting fixture element, such as a chandelier (not shown). Electrical conducting wires 15 connected with the electric lighting fixture element are projected through the 100 grooves 12—12 into the interior of the tubular member 5 and arranged for operative connection with electrical conducting means (not shown) that are ordinarily installed in the ceiling 2.

An integral lateral extension consists of arms 16 and 17 merging into the flange 10 and the loop 13, respectively, and a tubular portion 18 threaded exteriorly at 19 from the end thereof to a flange 20 for engagement with an elbow cap 21. The elbow cap 21 is maintained in adjusted position on the 105 110

tubular member 18 by a set screw 22. A switch 23 that is ordinary in construction is connected in an ordinary manner with the elbow cap 21 and is provided with the usual 5 pull cord 24. Electrical conducting members 25 extend from the electric lighting fixture elements (not shown) that have been heretofore referred to and are arranged to enter the switch 23 through the bore 26 of 10 the tubular member 18. A return wire 27 from the switch 23 is projected upwardly through one of the grooves 12—12 for operative connection with the electrical conducting means installed in the ceiling 2, as will 15 be understood.

From the foregoing description of the various parts of the device, the operation thereof may be readily understood. The switch 23 is supported adjacent to the stem 20 1 by the same means that supports the lighting fixture elements carrying the lamps controlled by the switch. Consequently, operation of such incandescent lamps is controlled 25 by means of the pull cord 24. Since the switch 23 is supported adjacent to the stem 1, it is obvious that a great saving in material and in the time required to install and assemble a complete lighting system is effected. In the usual assembly of the parts 30 of a complete lighting system, the switch is disposed in a suitable receptacle or the like attached to a wall at a considerable distance from the lamps controlled thereby and from the electrical conducting wires passing 35 through the stem 1. It is therefore necessary in the ordinary construction to insulate the fixture of which the stem is a part from the switch 23 and to provide electrical conducting means operatively connecting 40 the incandescent lamps depending from the stem 1 with the switch, such electrical conducting means ordinarily being imbedded in the wall. When my improved device is used, the work of installing and assembling 45 a complete system is reduced to a minimum and furthermore the assembly of the switch may be accomplished coincidently with the assembly of the fixture of which the stem 1 is a part and without additional labor. It 50 will be observed that a single member connected to a fixed support maintains the tubular member 5 in adjusted position, supports an electric lighting fixture element, (not shown) supports the switch for controlling the operation of the incandescent 55 lamp carried by the electric lighting fixture element, and serves as a means for guiding and carrying the electrical conducting wires embodied in the lighting system.

60 Referring now to Fig. 3, I have shown a modified form of the attachment in which the body portion 9 is formed with a threaded bore 30 adapted for connection with a threaded tubular member 31 that is connected at its upper end with a fixed support 65

and depends below the end of the tubular member 5 of the stem. The electrical conducting wires 15 are passed upwardly through the tubular member 31 and consequently the body portion 9 need not be provided with the grooves 12—12 illustrated in 70 Figures 1 and 2. The modified form of the device shown in Fig. 3 is otherwise identical with the preferred form of the device in essential respects and requires no further 75 description. The same reference numerals have been used to denote like parts throughout the several views.

In Fig. 4, another modification of the invention is illustrated in which the body portion of the attachment has the form of a ring 40 fitting a tubular member 41 that is included in the stem of the fixture to which the device is applied. A set screw 42 projected through a threaded opening 43 in 80 the link engages with the tubular member 41 to maintain the body portion in adjusted position. The tubular member 41 is formed with an inwardly extending flange 44 at its lower end resting upon alined shoulders 45 and 46 provided by cutting away the remote walls of a U-shaped end portion 47 of a rod 48 that extends through the tubular member 41 for engagement at its upper end with a fixed support (not shown). A lateral extension 49 to the body portion 40 is integral with the latter and fashioned to provide a tubular extremity 50 threaded at 51 and fashioned with a shoulder 52. The switch 23 is supported at the end of the 90 tubular extremity 50 by the cap 21 and maintained in adjusted position with respect thereto by the set screw 22. It will be understood that an electric lighting fixture element (not shown) is supported from the 100 U-shaped body portion 47 and that the electrical conducting wire 53 extends therefrom into the tubular member 41 at the lower end of the latter. Another electrical conducting wire 54 extends from the electric lighting 105 fixture element to the switch 23 through the tubular extremity 50 and a return wire 55 from the switch is arranged to enter the tubular member 41 at the lower end thereof. The operation of the modified form of the 110 device illustrated in Fig. 4 is otherwise identical with the operation of the preferred form of the device and consequently requires no further description.

I claim:

1. In an electric fixture, a stem comprising a vertically disposed rod supported at its upper end and threaded at its lower end, a tubular member arranged to encircle the rod, and means engaging with the rod at 125 the lower end thereof and contacting with the tubular member at its lower end for supporting the latter, said means comprising a flanged body portion provided with a threaded opening arranged to engage 130

the threaded rod and formed with a lateral extension adapted for connection with a switch and with a loop portion adapted for connection with means for supporting an element to depend therefrom, said body portion being formed with an opening therethrough adapted to guide an electrical conducting wire into the tubular member, and said lateral extension being formed with a bore for guiding an electrical conducting wire into the switch.

2. In an electric fixture, a stem comprising a rod, a tube disposed over said rod, a member having a threaded bore adapted to receive said rod and to be supported thereby, 15 said member being adapted to support said tubular member, and having a laterally extending tubular portion adapted to receive an electric light switch, and said member having a loop adapted to support an electric lighting fixture.

FRANK LOWELL BUTLER.
